United States Patent Office

Des. 229,160
Patented Nov. 13, 1973

229,160

SPONGE

Kenneth N. Meyer, Far End, Sea Lane,
Angmering-on-Sea, England

Filed Sept. 9, 1971, Ser. No. 179,261

Term of patent 14 years

Int. Cl. D7—05

U.S. Cl. D7—178

FIG. 1 is a perspective view of a sponge showing my new design;

FIG. 2 is a rear elevational view thereof;

FIG. 3 is a side elevational view thereof;

FIG. 4 is a top plan view thereof; and

FIG. 5 is a bottom plan view thereof.

I claim:

The ornamental design for a sponge, as shown and described.
